(57) **CLAIM**

I claim the ornamental design for a removable flooring installation gap spacer, as shown and described.

DESCRIPTION

FIG. 1 is a side elevation view of the removable flooring installation gap spacer, shown in place, between and making contact with, a flooring plank and a wall drywall panel;

FIG. 2 is a front, top and side elevation view of the removable flooring installation gap spacer;

FIG. 3 is a front, bottom and side elevation view of the removable flooring installation gap spacer;

FIG. 4 is a side elevation view of the removable flooring installation gap spacer;

FIG. 5 is an opposite side elevation view of the removable flooring installation gap spacer, wherein FIG. 5 is a mirror image of FIG. 4;

FIG. 6 is a rear view of the removable flooring installation gap spacer;

FIG. 7 is a front view of the removable flooring installation gap spacer;

FIG. 8 is a top plan view of the removable flooring installation gap spacer; and,

FIG. 9 is a bottom plan view of the removable flooring installation gap spacer.

The broken line showing of environment in FIG. 1 is included for the purpose of illustration only and forms no part of the claimed design.
